Application November 1, 1948, Serial No. 57,704

17 Claims. (Cl. 103—173)

1

The present invention relates to hydraulic mechanisms, and more particularly to a hydraulic mechanism which can be used either as a pump or as a hydraulic motor.

The present invention may be applied to the same general class of mechanisms as that set forth in my Patent No. 2,248,449 issued July 8, 1941, although it is not necessarily limited thereto.

The need for uses for high pressure hydraulic mechanisms for pumps and motors has increased greatly in recent years. Lighter units with higher operating pressures, and smooth, quiet operating characteristics have been desired by engineers in many fields for designing a wide variety of products. Among such products may be named, aircraft landing gear retractors, wing flap controls, tractor implement controls and truck hoisting mechanisms. While the mechanism of my above-mentioned patent works satisfactorily up to quite high pressures, and may be designed for use with hydraulic liquids having a wide range of viscosities, nevertheless it has limitations which it is one object of the present invention to overcome.

Another object of the invention is to make an improved high pressure hydraulic mechanism.

Another object is to make an improved hydraulic mechanism wherein pressures on working areas of the mechanism will be compensated for by substantially equal and oppositely disposed forces.

Another object is to make a hydraulic mechanism in which working clearances will be controlled by the viscosity of liquid flowing through the mechanism.

Another object is to make a hydraulic mechanism which has improved reversing characteristics.

Another object is to make a hydraulic mechanism with a floating valve compensator so that different pressures on various portions of one side of a rotating valve disc, will be compensated for by similar and opposed pressures on the reverse side of the valve disc.

Another object is to make a high pressure hydraulic mechanism with a rotating valve and a pressure control member, wherein a combination of balanced forces tends to reduce wear on the valve, and predetermined unbalanced forces urge the pressure control member toward a proper functioning relationship with the valve.

Another object is to equalize pressures on both sides of a valve disc while it is rotating and being

subjected to constantly varying pressures on different portions of both sides thereof.

These and other objects and advantages of the invention, which will appear later herein, are attained, in accordance with one feature of the invention, by pistons mounted to reciprocate in a plurality of parallel cylinders symmetrically arranged around the axis of a shaft having a wobble plate mounted thereon at an acute angle and eccentrically thereto, so as to reciprocate the pistons in a continuing cycle, a rotary valve disc being secured to rotate with the shaft over cylinder ports in one end of each of the cylinders, and having apertured valve openings therein arranged in predetermined relation to the wobble plate, the valve disc having a plurality of openings therethrough arranged to communicate with a plurality of recesses on an area facing the valve disc on the reverse side of the valve from the cylinders, the recesses being positioned similarly, and being of substantially equal area to the port openings from the cylinders, so as to effectively balance pressures on opposite faces of the valve disc; a viscosity compensating plate being preferably arranged at the reverse side of the valve disc from the cylinders and adapted to move or "float" longitudinally of the shaft under pressures transmitted to opposite sides thereof automatically to vary the clearances from the valve disc in accordance with the requirements of liquids having different viscosities flowing through the mechanism.

These and other features of the invention will be fully set forth in the following description and the accompanying drawings, wherein:

Fig. 1 is a longitudinal sectional view through a hydraulic mechanism embodying the present invention;

Fig. 2 is a sectional view taken in the plane of the line 2—2 of Fig. 1;

Fig. 3 is a sectional view taken in the plane of the line 3—3 of Fig. 1;

Fig. 4 is a sectional view taken in the plane of the line 4—4 of Fig. 1;

Fig. 5 is a fragmentary sectional view through a rotatable valve, taken in the plane of the line 5—5 of Fig. 1;

Fig. 6 is a sectional view taken in the offset planes of the broken line 6—6 of Fig. 1;

Fig. 7 is a fragmentary sectional view in the plane of the line 7—7 of Fig. 1, showing the pump shaft and wobble plate and an end portion of the cylinder block;

Fig. 8 is a longitudinal sectional view through an embodiment of a modified form of the invention, taken on the offset line 8—8 in Fig. 10, the

shaft and associated parts being rotated 180° from the position shown in Fig. 1;

Fig. 9 is a sectional view taken in the plane of the line 9—9 of Fig. 8;

Fig. 10 is a sectional view taken in the plane of the line 10—10 of Fig. 8;

Fig. 11 is a fragmentary longitudinal sectional view showing a modified pressure balancing and clearance controlling end plate structure of a mechanism otherwise similar to that shown in Fig. 8;

Fig. 12 is a fragmentary sectional view similar to Fig. 11, but showing a further modified end plate structure;

Fig. 13 is a sectional view taken in the plane of the line 13—13 of Fig. 12;

Fig. 14 is a sectional view taken in the plane of the line 14—14 of Fig. 12;

Fig. 15 is a diagrammatic view of a pump valve disc mounted over the cylinder ports similarly to Fig. 3 but in a different rotative position, and showing the angular relations of the various parts of one form of the invention when used as a hydraulic pump;

Fig. 16 is a diagram similar to Fig. 15 but showing the device arranged for use as a hydraulic motor;

Fig. 17 is an end elevational view of a main shaft taken from the left end thereof in Fig. 1, but with the shaft in a different angular position, showing the relative positions of a shaft axis and an eccentric shaft portion, a valve keyway, and a pair of hub keyways being shown in their relative angular positions; and

Fig. 18 is a transverse sectional view through an eccentric shaft portion, showing the outline of an axially tilted hub mounted thereon, the shaft having a wide keyway which permits a relative adjustment of the hub on a reversal of torque forces between the two parts.

Before entering into a detailed description of the device it is desired to point out that all forms of the invention are capable of being used either as a hydraulic pump or as a hydraulic motor. Where the term "pump" is used, it will be interpreted when practicable, through the specification and claims, to mean "pump or motor."

Referring to the drawings, and considering first the structure shown in Figs. 1 to 7, inclusive, the device will be described first in its use as a high pressure hydraulic pump which is one of its important uses.

Referring to the drawings, Figs. 1 to 7 inclusive, a cylinder block 20 may be of metal, and preferably is of steel, alloyed for toughness. It may be cast, forged or machined from bar stock. An axial bore 21 is machined through the cylinder block, and a friction reducing bearing sleeve 22 is mounted therein, rotatably to support a shaft 23 therein.

A plurality of cylinders 24, here illustrated as five, see Fig. 6, are machined in the cylinder block with their axes parallel to that of the shaft bore 21, and are preferably disposed symmetrically about it. The left-hand end of each cylinder, as shown in Fig. 1, which will be termed herein the outer end of the cylinder, opens into a cylinder port 25 in the cylinder block, see Fig. 6. The cylinder ports are in open communication with a valve chamber 27, which is also shown as formed in the cylinder block, see Figs. 3 and 4. The terms "inward" and "outward" as used throughout the present description designate toward, or away from, respectively, the inner or mounting end of the illustrated forms of the in-

vention, which is the right-hand end as shown in Figs. 1 and 8. This limitation does not however extend to the terminology of the claims, since the invention obviously is capable of various types of mountings.

A plurality of pistons 28 are mounted, one in each cylinder, to have a close sliding fit therein. These pistons are cup-shaped, and have wide angle cone-shaped heads 29. In establishing the clearance between the pistons and cylinder walls it should be borne in mind that the pistons will tend to expand under extremely high pressure. A coil spring 30 may be mounted in each piston, to be held in compression between the piston head and the outer end of the cylinder. No such springs are required when the device is intended for use only as a motor, since the pistons then will be forced inwardly by the pressure of the propelling liquid, as will be understood from a reading of the present description.

A piston actuating wobble plate 31 preferably is mounted on an axially tilted hub 33, as best shown in Fig. 7, which in turn is mounted on an eccentric portion 36 of the shaft 23 to embody the invention of my Patent 2,248,449 referred to previously herein. The annular plate 31 comprises a flanged disc, which is fitted onto the outer race of a ball bearing 32 of the thrust type. The inner race of the ball bearing 32 is fitted onto the axially tilted bearing support portion 33' of hub 33 which is disposed with the axis of said bearing support portion at an acute angle to that of the shaft 23 to which it is secured by a key 38.

The plane of the outer or left-hand face 31' of the wobble plate 31 which engages the ends of the pistons for actuation thereof is normal to the tilted axis of the bearing support portion 33' of the hub 33. The eccentric portion 36 of the shaft 23 upon which the hub 33 is mounted is eccentric to the shaft axis by an amount equal to, as set forth in my above-mentioned patent, the radial distance between the piston center circle defined by the axis of pistons 28 and the midpoint of a chord of such circle whose length is that of the piston stroke.

The action of the tilted hub mounted on the eccentric shaft portion causes the tilted axis of the wobble plate to precess in a generally conical path, with the exception of the circular precession of the hub itself caused by its eccentric mounting on the shaft. The high point of the eccentric is located approximately 90° in advance of the point of maximum inward or outward piston movement caused by the wobble plate as will be brought out later herein. This eccentric mounting of the wobble plate prevents radial sliding movement of the wobble plate across the piston heads during a high pressure stroke of the piston, thus greatly reducing wear of the area of contact between the wobble plate and the conical piston heads.

The inner end of the shaft 23 is mounted in a ball thrust bearing 34, which in turn is mounted in a domed closure cap 35. The cap is secured to the cylinder block as by cap screws 37. The inner end of the shaft projects inwardly beyond the closure cap for connection to a suitable driving or driven mechanism of a usual type.

A flange 39 on the shaft transmits the piston thrust on the shaft to the cap through the ball thrust bearing 34. A shaft seal 40 is mounted between the shaft 23 and the cap 35, and when the device is used as a pump with center intake, 75 is arranged to prevent leakage of air into the

pump between the shaft and the cap; since with the pump in operation in this manner pressure within the cap is reduced below atmospheric, as will be brought out later herein. A hole 41 through the shaft provides a pressure equalizing passage as shown in Figs. 1, 7 and 8, between the interior of the closure cap 35 and the center of the valve chamber 27.

A valve disc 42 is keyed to the shaft 23 to rotate therewith, as by a key 56 engaging keyways 55 and 55' in the shaft and valve disc respectively. A key anchoring pin 56' is mounted in the keyway 55' in the valve disc 42 as shown in Figs. 3, 4, and 5, to prevent the key from working outwardly toward an end closure plate 43. The valve is fitted accurately between the ported cylinder end 27' of the valve chamber 27, and the outer end closure plate 43. The end closure plate 43 is secured in place by cap screws 44 to provide a housing including the cylinder block or body portion 20 and the closure plate 43. All fits between the ported valve chamber face 27' of the cylinder block, the sides of the valve disc 42, and end plate 43 are ground to close tolerances so as to provide suitable sealing engagement of the valve disc with opposite sides of the valve chamber. If a gasket is desired to seal the joint between the cylinder block and the end plate, its thickness must be considered in designating dimensions. For example, with hydraulic fluids having a viscosity range from 150 to 250 Saybolt sec. at 100° C. and intended to operate in the temperature range from 0° to 200° F. the total clearance for both sides of the valve disc may be from .00075" to .0015". The amount of clearance of course is a design factor and will vary with size, volume, pressure and other factors.

The valve disc 42 has a pair of arcuate port openings 47 and 48 therethrough disposed to register with successive cylinder port openings 25 upon rotation of the shaft 23. The valve port 47 is the intake, for the purpose of the present description, and the port 48 is the outlet. Grooves 49 and 50 are provided for lubricating areas of the valve faces radially beyond the ports. From the inlet port 47 a passage 51 is notched out of the outer or left-hand side of the valve radially inwardly from the inlet port 47, to communicate with an inlet opening 52 in the end closure plate 43. The inlet opening 52 is threaded to receive a usual liquid supply pipe for supplying hydraulic liquid to the pump. The shaft 23 terminates short of the end plate 43 to provide an inlet passage through the central bore of valve 42 to the passage 51 and thence to the valve inlet port 47.

The outlet port 48 of the valve communicates through radially outward openings 48' in the valve, with an annular outlet chamber 53 surrounding the valve. This annular outlet chamber is provided by a substantial lateral clearance between the periphery of the valve and the valve chamber side wall. A threaded outlet opening 54 from the outlet chamber is threaded to receive a usual outlet pipe. A pair of small relief holes 57 and 58 are provided one slightly beyond each end of the valve outlet port 48 to communicate between the cylinders and the opposite side of the valve disc during delayed opening of the outlet port as will be brought out later herein.

In order to balance the pressures on opposite sides of the valve disc 42 a plurality of pressure balancing recesses 59 are provided in the end closure plate 43 facing said valve disc. These recesses are equal in size and shape to the cylin-

der ports 25 and are located opposite them, so that whenever one of the valve ports 47 or 48 or openings 57 or 58 is in communication with a cylinder port 25, it also communicates with a recess 59 of equal area. Thus, whatever pressures, positive or negative, the inner face of the valve is subjected to from the cylinder ports, equal and opposite pressures are transmitted, by liquid pressure, through the valve ports 47 and 48, and the smaller openings 57 and 58, by means of the recesses 59 to the opposite face of the valve disc. This simple arrangement, by tending to balance the constantly varying pressures from the cylinders during operation on both sides of the valve disc, greatly reduces valve wear. It also increases the pressure capacity of the pump by reducing valve friction to a minimum even at extremely high pressures, for example four thousand pounds to the square inch outlet pressure.

As previously stated, in the form of the invention shown in Figs. 1 to 7 inclusive, the maximum and minimum viscosities of the liquid to be used must be considered in establishing the clearances between the faces of the valve disc and the valve chamber. Since the viscosity of the oils or other hydraulic fluids changes greatly with variations in temperature, and since it is not always possible or practicable to retain the hydraulic fluid within reasonably narrow temperature ranges, the efficiency of the mechanism shown in Figs. 1 to 7 will vary when the viscosity of the liquid passes beyond design limits in either direction.

Figs. 8 to 10 inclusive show a modified form of the invention. This modification gives highly efficient operation with liquids having a wide range of viscosities. This embodiment also will be described first as a pump, although it is also capable of use as a motor as will be brought out later herein.

The entire mechanism of Fig. 8 to the right of the plane of the section line 10—10 is the same as that shown in Fig. 1. These previously described parts therefore will be designated by the same reference numerals as in Fig. 1. Since they operate in a similar manner, their functions will be understood from a reading of the foregoing description thereof.

With respect to the outer or left-hand end assembly illustrated in Figs. 8 to 10 inclusive, however, a modified form of end closure plate 60 is secured to the outer end of the cylinder block 20 as by cap screws 61. The closure plate 60 has a central threaded opening 62 therein, which for the purpose of the present description will be referred to as the inlet opening, although, as will be brought out later herein, it may comprise the outlet.

An annular recess 63 is provided in the inner face of the closure plate 60, and the housing means defining the valve chamber 27 includes a pressure control plate or backing plate 64 mounted in the recess 63 with a substantial amount of lateral clearance as shown at 63' between its periphery and the side wall of the recess to provide open communication between the annular outlet chamber 53 and the rear face of the pressure control plate 64. The inner end face of plate 64 forms the outer side of valve chamber 27 and is adapted to bear more or less closely against the outer face of valve disc 42 whose inner face, as before, bears against the end face 27' of the cylinder block at the inner side of the valve chamber, and the combined axial length of members 42 and 64 is somewhat less than the axial distance between the outer end face of recess 63

and the ported cylinder block end face 27' so as to provide a space 66 between the outer face of the pressure control plate and the closure plate 60, which comprises in effect a hydraulic chamber for urging the pressure control plate toward the valve disc to maintain suitable sealing engagement of the inner and outer faces of valve disc 42 with the opposite sides of the valve chamber 27. The pressure control plate 64 has an outward tubular flanged extension 65 thereon which fits slidably into the inner end of the inlet opening 62, and is sealed therein by a hydraulic O-ring 67. This permits limited axial movement of the pressure control plate in its recess toward and away from the outer face of the valve disc 42.

The pressure control plate 64 has pressure balancing recesses 68 in the inner face thereof in a manner similar in shape, size and position to the recesses 59 in the fixed end closure plate 43 of Fig. 1. From each of the pressure balancing recesses 68, two small holes 69 and 70 extend through the pressure control plate 64. Each of these holes opens into a separate cylindrical recess 71 in the outer face of the pressure control plate 64.

The bottom of the recess 63 in the end closure plate 60 also has a plurality of cylindrical recesses 72 therein, similar, and similarly located, to those in the pressure control plate 64. A corresponding plurality of small floating sealing sleeves 73 are provided, each mounted with one of its ends in a recess 71 in the pressure control plate 64, and its other end in the corresponding recess 72 in the end closure plate 60. Hydraulic O rings 74 and 75 seal the ends of each sleeve 73 in its respective recesses. These sleeves act simply as sealing devices, to seal off the inner ends of recesses 71 from the space 66 at the outer end of the pressure control plate, and to expose these inner ends to the pressure from the pressure balancing recesses 68.

As will be brought out in a description of the operation of the device later herein, there is at least one of the openings through the valve disc 42 in open communication with each cylinder port 25 throughout substantially the entire cycle of rotation of the valve. Therefore the pressure of each cylinder, at its cylinder port 25, will be transmitted through one of the valve ports 41 or 48 or one of the small holes 57 and 58, which is in registry with the cylinder port, to the pressure balancing recess 68 which is opposite that particular cylinder port, and thence through the holes 69 and 70 in the pressure control plate leading from the pressure balancing recess to the inner ends of the two corresponding cylindrical recesses 71 in the pressure control plate 64. This latter pressure in the recesses 71 urges the pressure control plate 64 toward the valve disc with a rotatively varying pressure similar to that of the pressure balancing recesses 68. The amount of the force exerted by this pressure will be controlled of course by the design of the area of the cylinders 71.

The overall effective area of the heads of the cylindrical recesses 71, preferably is equal to the maximum effective pressure areas on the inner face of the pressure control plate which they are intended to balance. These areas are those under pressure, through the liquid film on the face of the valve, from the outlet port in the valve, and from the outlet chamber 53 around the valve disc.

It is clear that a relatively negative pressure 75

will exist in the intake port 47 of the valve and in each of the cylinder ports 25 during an intake stroke of its piston when the device is operating as a pump. But regardless of whether the pressure at the cylinder port is positive or negative it will be balanced on the valve disc and on the pressure control plate 64 during the entire rotative movement of the device.

In addition to this constantly varying compensating pressure, an overall pressure is maintained on the exposed rear area of the pressure control plate 64 by the open communication between the annular outlet chamber 53 and the space 66 at the outer face of the plate 64, through the clearance space 63'. Any tendency for the clearance between the valve disc and the pressure plate 64 to increase beyond an effective sealing condition would permit oil to flow across the face of the valve disc and thus would decrease the pressure on the inner face of the pressure control plate 64.

This would cause the pressure control plate to be moved inwardly by the hydraulic pressure on its outer face. However, since a greater pressure is required to maintain a predetermined clearance between the faces of the valve disc and its opposed chamber faces, with a more viscous than with a less viscous fluid, the amount of clearance at these points will vary automatically with changes in viscosity of the fluid.

With this construction of Figs. 8 to 10 inclusive, it is preferred to fit the valve disc on the shaft 23 with a close sliding fit, so that the valve disc can center itself between the two opposed faces between which it operates and thus will tend to adjust the clearances on both faces of the valve in accordance with varying pressures and viscosities which may exist during operation.

In order to assure seating of the pressure control plate 64 against the valve disc 42 under relatively low outlet pressure conditions, I have shown compression springs 77 extending through central bores in the sleeves 73 and bearing at their ends against the plate 64 and the end plate 60 so as to exert a moderate inward thrust resiliently urging the plate 64 against the valve disc. Under ordinary operating conditions, however, the compression springs 77 are not necessary. With these springs omitted, and using liquids of medium to heavy viscosities, usually within one-half revolution or less of the shaft 23 the outlet pressure against the outer face of the pressure control plate, will seat the pressure control plate against the valve disc, thereby placing the device in operative condition.

In the further modified form of the invention shown in Fig. 11 the same general type of recessed pressure balancing plate and sealing sleeves therefor are employed as shown in Figs. 8 to 10 inclusive. The same reference numerals therefore which were employed in connection with Figs. 8 to 10, inclusive, will be employed in connection with Fig. 11, adding thereto the suffix "a." This latter modified form of the invention is designed to permit operation by reversing the relative positions of the inlet and outlet ports. When the direction of shaft rotation is reversed, for example, from that of Figs. 8 to 10 inclusive, the central opening 62a in the end closure plate 60a, which was the inlet 61 in the form shown in Fig. 8, now will be the outlet.

In this embodiment of Fig. 11, a hydraulic O ring 78 seals the periphery of a pressure control or balancing plate 64a to the wall of its recess 63a in the end closure plate 60a. A pair

of ball check valves 79 and 80 are mounted in the ends of a coil compression spring 81 and are urged thereby toward opposite ends of a valve recess 82. The outer ball check 80 is seated in the end of a passage 83 which communicates with the opening 62a in the outer end closure plate 60a (now the outlet, previously in Fig. 8, described as the inlet opening). The inner ball check 79 is seated in the end of a passage 84 which communicates with the annular inlet chamber 53a (previously described as the outlet chamber). A lateral passage 85 communicates from the valve recess 82 with the space 66a at the exposed rear or outer face of the pressure control plate 64a. Thus, regardless of whether the annular chamber 53a, or the opening 62a is under the greater pressure, the higher pressure will be transmitted to the outer face of the pressure control plate 64a, and the low pressure side will be sealed off from this area by its ball check valve.

Another modified form of the invention is illustrated in Figs. 12, 13 and 14. This modification comprises a pressure balancing plate assembly which is shown as mounted on the end of a cylinder block and valve assembly similar to that shown in Figs. 1 and 8. The modification shown in Figs. 12 to 14, inclusive, is limited as to the maximum pressure which it is capable of developing. In this manner, it comprises, in effect, its own safety valve.

In this latter form of the invention an annular intermediate spacing member 90 is provided between an end closure plate 91 and the body or cylinder block 20 of the device. These parts are held in assembled relation on the cylinder block 20 by cap screws 92. The annular spacing member 90 has an inner bore portion 93 of reduced diameter, and an enlarged outer bore portion 94, with an offset shoulder 95 between the two bore portions. A pressure control plate 97 is mounted for limited axial movement in the offset bore of the intermediate spacing member 90, and is sealed peripherally in the reduced bore portion 93 thereof by a hydraulic O ring 98. The pressure control plate 97 is mounted to provide the desired working clearance on both sides of the valve disc. The pressure control plate 97 has a plurality of pressure balancing recesses 99 in its inner face similar to the recesses 59 in the end closure plate 43 of Fig. 1.

A plurality of strong compression springs 100 are seated in recesses 101 in the outer face of the pressure control plate 97, and bear against the end closure plate 91 to urge the plate 97 inwardly toward the shoulder 95. Since the outer face of the pressure control plate 97 is sealed by the O ring 98 from the higher pressure of the annular outlet chamber 53, and is open only to the lower pressure of an inlet opening 102 in the end closure plate 91, the springs 100 provide the only stabilized pressure urging the pressure control plate 97 inwardly toward the valve disc. This spring pressure may be compared to that supplied in the modification of Figs. 8 to 10 inclusive by the outlet pressure applied to the exposed area of the outer face of the plate 64.

A rotative varying pressure balancing arrangement somewhat similar to that provided by the sleeves 73 and cylinders 71 in the embodiment shown in Figs. 8 to 10 is provided for balancing the pressures imposed by the actions of the pistons 28 in cylinders 24 upon operation of the device.

From each of the pressure balancing recesses

99 in the inner face of the pressure control plate 97, a hole 103 communicates with a cylindrical recess 104 in the outer face of the pressure control plate 97. These cylindrical recesses each have a top area, other than that of the hole 103, equal substantially to the pressurized areas of the valve disc to be balanced as previously described in connection with the embodiment illustrated in Figs. 8 to 10, inclusive. A sealing 10 plug 105 is mounted in each of the cylindrical recesses 104 to be free for relative axial movement therein. The inner end portion of each plug is sealed to its cylinder wall by a hydraulic O ring 107, and the outer end thereof bears 15 against the end closure plate 91.

In this modified construction of Figs. 12 to 14, inclusive, the springs 100 urge the pressure control plate 97 inwardly into operative position against the valve disc 42 to resist the pressures 20 which tend to move the plate 97 away from the valve disc. Additionally the plugs 105 seal the cylinders 104 and thereby cause the pressure 25 transmitted through the liquid from each of the cylinders 24 with which the pressure balancing recesses 99 are in communication, to be transmitted through the holes 103 to the inner ends 30 of the cylindrical recesses 104. This transmits rotatively balancing forces substantially equal and opposite to those imposed by the constantly 35 varying fluid pressures from each of the cylinders 24.

With this latter modification of the device, when the outlet or higher pressure exerts a separating force between the valve faces and their 40 opposed valve chamber surfaces which exceeds the contrary force exerted on the pressure control plate by the springs 100, the pressure control plate 97 will be forced outwardly away from the valve disc 42, and permit excess fluid to bypass between the valve inlet and outlet ports 47 and 48. Thus the pump will not generate pressures exceeding that determined by the total 45 pressure of the springs 100. This is a valuable asset under some operating conditions wherein the pump contains its own limitation as to the maximum pressure which may be generated by it. At pressures below this maximum cutout pressure, the plate 97 will be moved outward slightly to develop a proper operating clearance 50 by liquids having a higher viscosity in the same manner as described for the form shown in Figs. 8 to 10, inclusive.

Up to this point in the present description, the various forms of the invention have been described only in their use as pumps. This was done to facilitate an understanding of the functions of the various mechanisms and the hydraulic operations involved.

In changing the use of a device embodying the invention from pump to motor, or vice versa, or in reversing its direction of rotation without changing its function, two principal factors must be borne in mind; first, that in order for the wear compensating feature of my previously designated former Patent 2,248,449 to operate the offset of the high point of the eccentric portion 36 of the shaft 23 must be approximately 90° of shaft rotation ahead of piston movement at the initiation of a power stroke, and, second, that what has been termed the outlet port (48 of the valve disc) should preferably register with each piston port on its high pressure stroke. As a pump the outward stroke of the piston will be the power or higher pressure stroke, while as a

motor the inward stroke is the higher pressure or power stroke.

One method of accomplishing the wear compensating adjustment for either direction of rotation, either as a pump or as a motor, is by providing alternately usable keyways 45 and 46 for the eccentric hub 36 (see Fig. 17). These keyways are arranged so that with the hub keyed to the proper keyway, the intake and exhaust valve ports will open respectively into each cylinder port 25, 12° of shaft rotation after the piston in that cylinder has started on its high and low pressure strokes, respectively, as illustrated in the diagrams of Figs. 15 and 16. Also by providing for substantial reversal of the operative position of the eccentrically mounted hub 33, the parts can be arranged so that the relative position of the high point of the eccentric shaft portion 36 will be approximately 90° ahead of the point of contact of each piston with the wobble plate at the beginning of the power stroke of that piston. By this arrangement the wear compensating feature of my prior Patent 2,248,449 can be made to occur on the high pressure stroke regardless of whether the device is used as a pump or a motor, or is rotating in one direction or the other.

In order more easily to visualize the operation of the device, a brief description will be given of two operative arrangements of the invention, one as a pump and one as a hydraulic motor, both having the same direction of rotation. From these it will be easy for one familiar with the art to visualize these same operations in a reverse direction.

The arrangement and angular extent of the cylinder ports and valve ports illustrated are for a device having a 12° delayed opening both on the intake and outlet ports. It will be noted in Fig. 17 that the valve keyway 55 is on a diameter of the shaft 23, while the two keyways 45 and 46 in the eccentric portion 36 of the shaft 23 are each offset 6° from a diameter of the eccentric portion 36 of the shaft. The reason for this will be brought out in the following description of operation.

In Fig. 15, which illustrates the device set up for operation as a pump with counterclockwise rotation as viewed from its outer end, the valve disc 42 is shown in its position at the beginning of a power or outward stroke of the piston mounted in the cylinder beyond the cylinder port 25a. In this position, the valve keyway 55, as shown in Fig. 17, would be diametrically opposite a point midway between the ends of the valve outlet or high pressure opening 48 and the valve inlet or low pressure opening 47. In the indicated structure this would be 31° ahead of a line 110 marking the leading edge of the valve outlet opening 48. However, in the position of the parts illustrated in Fig. 15, this line 110 is 12° back of the edge of the cylinder port 25a, the position of which is indicated by a line 111. At this point, the small opening 57 is just opening into the cylinder port 25a.

The pistons in the cylinders opening into the cylinder ports are centered relatively to the angular length of the cylinder ports. Therefore, in order for the innermost point of the wobble plate to be centered on the piston in the cylinder opening into the port 25a, in Fig. 15, the innermost point of the wobble plate must be 25° ahead of the line 111 since, as indicated by lines 111 and 112 the angular length of each of the cylinder ports is 50°.

If the wobble plate hub keyways 45 and 46 were diametrically in line with the valve keyway 55, the innermost point of the wobble plate would be diametrically opposite the valve keyway and thus would be only 31° ahead of the line 110 since that would be the mid-point of the 62° angle between the adjacent ends of the valve disc intake and outlet ports 47 and 48. This then would bring the innermost point of the wobble plate only 19° ahead of the line 111 at which the piston should initiate its stroke. It is for this reason that the 6° offset of the hub keyways 45 and 46, shown in Fig. 17, is provided so as to move the position of the wobble plate relatively 6° ahead and thus to bring it at the midpoint of each piston at the desired initial position of its power stroke.

The power stroke continues through an angle of shaft rotation of 180°. The pressure generated in the cylinder during this first 12° of the power stroke before the valve opens is equalized on opposite sides of the valve disc through the small opening 57 which communicates with the pressure balancing recess facing the opposite side of the valve.

This first 12° of rotation gives the cylinder an opportunity to build up pressure approximately to match that in the annular outlet chamber 53. This reduces surging and makes for smooth operation. The outlet valve port 48 opens into cylinder port 25a after this 12° of travel and remains in communication therewith through the 118° of its length, plus the 50° length of the cylinder port. This makes a total of 180°, so that the outlet valve port 48 closes with respect to cylinder port 25a simultaneously with the completion of the power stroke, at which time the outlet port 48 is in the position of the intake port 47 in Fig. 15, and the intake port 47 is in the position of outlet port 48 in Fig. 15.

The intake stroke then immediately commences, but the inlet valve port 47 remains closed with respect to cylinder port 25a for an initial 12° during which time the cylinder develops a desired negative pressure so that there again will be no surge on the intake stroke. During this 12° of initial travel on the intake stroke, the cylinder port 25a is in communication with the pressure balancing recess facing the opposite side of the valve disc through the second small opening 58. The intake valve port similarly remains open throughout the 118° of its length plus 50° of cylinder port length and closes at the completion of the 180° intake stroke. This completes the 360° cycle.

For operation as a pump, the hub 33 is keyed to the eccentric 36 so that the high point or maximum eccentricity of the eccentric portion 36 of the shaft 23, is, as indicated in Fig. 15, approximately 90° ahead of the innermost point of the wobble plate. In the arrangement shown in Fig. 16, where the device is to be operated as a hydraulic motor, the hub 33 is keyed to the other keyway 46 on the eccentric shaft portion 36. This brings the high point or maximum eccentricity of the eccentric shaft portion 36 approximately 90° ahead of the outermost point of the wobble plate.

Since, when the device is used as a hydraulic motor, the inward stroke of the piston as illustrated in Fig. 1 is the power stroke, the high pressure (previously outlet) valve opening 48 now is positioned to open into the cylinder port 25a, at the initiation of an inward stroke of the piston. This is brought about by the reversal of the posi-

tion of the wobble plate. The outermost point of the wobble plate in this arrangement, due to the 6° offset of the keyway 46, is positioned directly in line with the center of the piston in the cylinder opening into the cylinder port 25a. With these exceptions, the cycle follows substantially the same course described above for Fig. 15, but with the further exception that the 12° portion of each stroke when the valve is closed is at the termination of the piston stroke instead of at the beginning, and the balancing of pressure through the apertures 57 and 58 takes place during this portion of the stroke.

Where it is contemplated that reversal of the device will be frequent, if desired, the metal of the shaft between the two keyways 45 and 46 may be removed, as shown at 114 in Fig. 18, so that the key 38 then is free to swing from one end to the other of this widened keyway. Upon reversal of direction of the shaft 23, the hub 33 will rotate relatively to the shaft until the key 38 abuts against the other end of the widened keyway. With this arrangement, no reseating of the key for reverse rotation would be necessary and the previously described readjustment for reversal would be automatic. This feature is particularly useful in conjunction with the embodiment shown in Fig. 11.

In the embodiment of Figs. 8 to 10, inclusive, it would not be feasible to operate the device either as a pump or a motor with the higher pressure applied to what has been described as the pump inlet opening 62. In such case the higher pressure could not reach the rear face of the pressure control plate 64, which, as previously set forth, is necessary in this embodiment for successful operation of the device.

In the embodiment illustrated in Fig. 11, it would be feasible to operate the device as a pump or hydraulic motor with the higher pressure applied to the inlet opening 62a, since, as previously brought out, the ball checks 79 and 80 act to apply the higher pressure to the rear face of the pressure control plate 64a regardless of which opening is used as the high pressure side.

In the embodiment shown in Figs. 12 to 14, inclusive, it also would not be feasible to apply the higher pressure to the central opening in the end plate 91.

While I have illustrated and described a preferred form of my invention, and some modifications thereof, it will be apparent to those familiar with the art that the device is capable of several additional modifications without departing from the spirit of the invention. It is desired, therefore, not to limit the invention except as set forth in the following claims.

I claim:

1. A hydraulic mechanism comprising housing means having a plurality of parallel cylinders therein arranged symmetrically around a central shaft bore in said housing means, a piston mounted to reciprocate in each cylinder, said housing means defining a valve chamber adjacent one end of said cylinders and substantially concentric with the shaft bore, and also defining a port at said one end of each cylinder in communication with one end of said valve chamber, a shaft rotatably mounted in said bore, a rotary valve mounted on said shaft to rotate therewith in said valve chamber and to overlie said ports, one side face of said valve seating against said one end of the valve chamber, said valve having intake and outlet ports therein adapted alternately to register with said cylinder

ports in cyclical succession, said housing means including a plate mounted to have seating engagement with the opposite side face of said valve from that seated against said one end of the valve chamber, said plate having a plurality of recesses therein adapted to communicate with the cylinder ports, said recesses being of similar size and shape, and disposed endwise oppositely to said cylinder ports, and drive means operatively interconnecting said shaft and said pistons to rotate said valve and to reciprocally move said pistons synchronously with the rotation of said shaft.

2. A hydraulic mechanism comprising housing means having a plurality of parallel cylinders therein arranged symmetrically around a central shaft bore in said housing means, a piston mounted to reciprocate in each cylinder, said housing means defining a valve chamber adjacent one end of said cylinders and substantially concentric with the shaft bore, and also defining a port at said one end of each cylinder in communication with one end of said valve chamber, a shaft rotatably mounted in said bore, a rotary valve mounted on said shaft to rotate therewith in said valve chamber and to overlie said ports, one side face of said valve seating against said one end of the valve chamber, said valve having intake and outlet ports therein adapted alternately to register with said cylinder ports in cyclical succession, said housing means including a backing plate mounted in said valve chamber to have resilient seating engagement with the opposite side face of said valve from that seated against said one end of the valve chamber, said backing plate having a plurality of recesses therein adapted to communicate with the cylinder ports through the valve intake and outlet ports, said recesses being of similar size and shape, and disposed endwise oppositely to said cylinder ports, and drive means operatively interconnecting said shaft and said pistons to rotate said valve and to reciprocally move said pistons synchronously with the rotation of said shaft.

3. A hydraulic mechanism comprising housing means having a plurality of parallel cylinders therein arranged symmetrically around a central shaft bore in said housing means, a piston mounted to reciprocate in each cylinder, said housing means defining a valve chamber adjacent one end of said cylinders and substantially concentric with the shaft bore, and also defining a port at said one end of each cylinder in communication with the inner end of said valve chamber, a shaft rotatably mounted in said bore, a rotary valve mounted on said shaft to be free for limited slidable movement thereon, and mounted to rotate therewith in said valve chamber and to overlie said ports, the inner side face of said valve seating against said inner end of the valve chamber, said valve having intake and outlet ports therein adapted alternately to register with said cylinder ports in cyclical succession, said housing means including a pressure control plate at the outer end of the valve chamber movable toward and away from the valve and having its inner side in seating engagement with the outer side face of the valve, hydraulic pressure control means operatively connected to transmit pressure from the cylinders to the outer side of the pressure control plate to urge the latter toward the valve, and drive means operatively interconnecting said shaft and said pistons to rotate said valve and reciprocally to

move said pistons synchronously with the rotation of said shaft.

4. A hydraulic mechanism comprising housing means defining a cylinder, a piston mounted to reciprocate therein, a shaft rotatably mounted adjacent said cylinder, said housing means also defining a valve chamber and a port in a side thereof opening into said cylinder, said housing means including a pressure control plate mounted on the other side of said chamber from said port, and movable toward and away from said ported side, said shaft extending into said valve chamber, a valve mounted on said shaft to rotate therewith, said valve being disposed in said valve chamber between said ported side and said pressure control plate, said valve having a high pressure port and a low pressure port therein, and a passage communicating from the high pressure valve port to the face of said pressure control plate outwardly from said valve to urge the pressure control plate toward sealing engagement with the valve disc.

5. A hydraulic mechanism comprising housing means defining a cylinder, a piston mounted to reciprocate therein, a shaft rotatably mounted adjacent said cylinder, said housing means also defining a valve chamber and a port in a side thereof opening into said cylinder, said housing means including a pressure control plate mounted on the other side of said chamber from said port, and movable toward and away from said ported side, an area of said pressure control plate at the side thereof away from the valve chamber comprising a portion of a hydraulic chamber, said shaft extending into said valve chamber, a valve mounted on said shaft to rotate therewith, and free for limited adjusting movement axially thereof, said valve being disposed in said valve chamber between said ported side and said pressure control plate, said valve having a high pressure port and a low pressure port therein, said pressure control plate having an opening therein adapted to communicate between the valve high pressure port and said area of the pressure control plate to urge the pressure control plate toward sealing engagement with the valve disc.

6. A hydraulic mechanism comprising housing means defining a cylinder, a piston mounted to reciprocate therein, a shaft rotatably mounted adjacent said cylinder, said housing means also defining a valve chamber having a port in a side thereof opening into said cylinder, said housing means including a pressure control plate mounted on the other side of said chamber from said port, and movable toward and away from said ported side, said shaft extending into said valve chamber, a valve mounted on said shaft to rotate therewith, said valve being disposed in said valve chamber between said ported side and said pressure control plate, the valve chamber being of greater diametrical width than the valve or the pressure control plate to provide a marginal area in open communication with the face of the pressure control plate outwardly from the valve, said valve having a high pressure port and a low pressure port therein, and a passage communicating from the high pressure valve port to said open marginal area.

7. A hydraulic machine comprising housing means defining a cylinder, a piston mounted to reciprocate in the cylinder, said housing means also defining a valve chamber having opposite sides thereof substantially flat and a port in one of said flat sides in communication with the cylinder, the opposite flat side having a recess cor-

responding in area and extent to the port, a valve mounted for rotation parallel to and between the opposite sides of the valve chamber to have sealing engagement therewith, said valve having an opening therein adapted to communicate between the port and the recess, and means for coordinating movements of the valve with those of the piston.

8. A hydraulic machine comprising housing means defining a cylinder, a piston mounted to reciprocate in the cylinder, said housing means also defining a valve chamber having opposite sides thereof substantially flat and a port in one of said flat sides in communication with the cylinder, the opposite flat side having a recess corresponding in area and extent to the port, a valve mounted for rotation parallel to and between the opposite sides of the valve chamber to have sealing engagement therewith, said valve having an intake port and an exhaust port therein adapted to communicate alternately between the cylinder port and the recess, and means for coordinating movements of the valve with those of the piston.

9. A hydraulic machine comprising housing means defining a cylinder, a piston mounted to reciprocate in the cylinder, said housing means also defining a valve chamber having opposite sides thereof substantially flat and a port in one of said flat sides in communication with the cylinder, the opposite flat side having a recess corresponding in area and extent to the port, a valve mounted for rotation parallel to and between the opposite sides of the valve chamber to have sealing engagement therewith, said valve having an intake port and an exhaust port therein adapted to communicate alternately between the cylinder port and the recess, the valve ports being spaced apart an angular distance greater than the angular extent of the cylinder port, the valve having an opening therein sealed from said valve ports and located in the angular area between the valve ports, said opening being adapted to communicate between the cylinder and the recess, and means for coordinating movements of the valve with those of the piston.

10. A hydraulic machine comprising housing means defining a cylinder, a piston mounted to reciprocate in the cylinder, said housing means also defining a valve chamber and a cylinder port opening therefrom into the cylinder, a valve rotatably mounted in the valve chamber, said valve having intake and exhaust ports therein adapted to register with the cylinder port, said housing means including a valve support element engaging the side of said valve opposite to said cylinder opening, said valve support element having a pressure balancing recess therein of approximately the same area and extent as the cylinder port, and means for coordinating movement of the valve and piston.

11. A hydraulic machine comprising housing means defining a cylinder, a piston mounted to reciprocate in the cylinder, said housing means also defining a valve chamber and a cylinder port opening therefrom into the cylinder, a valve rotatably mounted in the valve chamber over said cylinder port, said valve having intake and exhaust ports therein adapted to register with the cylinder port, and a valve support element adapted to conform closely to the side of the valve opposite to that over the cylinder port, said valve support element having a pressure balancing recess therein facing the valve of approximately the size and shape of the cylinder port, said recess

being in communication with the cylinder port, and means for coordinating movement of the valve and piston.

12. A hydraulic machine comprising housing means defining a cylinder, a piston mounted for reciprocation therein, said housing means also defining a valve chamber and a port in an end thereof opening into said cylinder, a recess in an opposite end of said valve chamber from said port, a valve rotatably mounted in said valve chamber and having oppositely disposed faces thereof in sealing engagement with said ported end and with said recessed end of said valve chamber, said valve having intake and exhaust ports therein adapted to register with the cylinder port and having an opening therein adapted to communicate between the cylinder port and the recess to transmit balancing pressures from the cylinder to opposite faces of the valve, and means for coordinating movement of the valve and piston.

13. A hydraulic machine comprising housing means defining a cylinder, a piston mounted for reciprocation therein, said housing means also defining a valve chamber and a port in an end thereof opening into said cylinder, said housing means including a pressure control plate mounted at the opposite end of said valve chamber from said port, a valve rotatably mounted in said valve chamber and having sealing engagement with said ported end of said valve chamber and with said pressure control plate and having intake and exhaust ports therein adapted to register with the cylinder port, said pressure control plate having a pressure balancing recess in the side thereof in sealing relation with the valve, said valve having an opening therein adapted to communicate between the cylinder port and the recess to transmit balancing pressures from the cylinder to opposite sides of the valve, means acting on said pressure control plate to urge it toward sealing relation with the valve, and means for coordinating movement of the valve and piston.

14. A hydraulic machine comprising housing means defining a cylinder, a piston mounted for reciprocation therein, said housing means also defining a valve chamber and a port in an end thereof opening into said cylinder, said housing means including a pressure control plate mounted at the opposite end of said valve chamber from said port, a valve rotatably mounted in said valve chamber and having sealing engagement with said ported end of said valve chamber and with said pressure control plate and having intake and exhaust ports therein adapted to register with the cylinder port, said pressure control plate having a pressure balancing recess in the side thereof in sealing relation with the valve and having a hole therein from the pressure balancing recess to a hydraulic cylinder formed in said pressure control plate, said valve having an opening therein adapted to communicate between the cylinder port and the recess to transmit pressure balancing pressures from the cylinder to opposite sides of the valve, and to the hydraulic cylinder in the pressure control plate, and means for coordinating movement of the valve and piston.

15. The arrangement set forth in claim 14, the margin of the pressure control plate being sealed from the opening in the valve, and a spring acting on said pressure control plate and urging it toward the valve.

16. A hydraulic machine comprising: housing means defining a plurality of parallel cylinders, a valve chamber adjacent the forward ends of said cylinders, and a plurality of cylinder ports communicating between said valve chamber and the forward ends of the respective cylinders; a piston mounted for reciprocation in each of said cylinders; a drive shaft mounted for rotation and having its axis parallel to the cylinders, said shaft extending within the valve chamber; said cylinders and pistons being disposed at angularly spaced positions about the axis of the shaft, and the longitudinal axes of the pistons defining a piston center circle about said shaft axis; a valve mounted on said shaft within said valve chamber and having an intake port and an exhaust port angularly spaced from each other and positioned to register with the cylinder ports; a wobble plate mounted about said shaft rearwardly of said pistons and having a forward face engaging the pistons at their rearward ends, said wobble plate having an axis normal to said forward face and inclined at a predetermined angle relative to the shaft axis to control reciprocation of the pistons between a rearward position engaging the rearmost portion of said forward face and a forward position engaging the foremost portion of said forward face; means mounting the wobble plate on said shaft so that said inclined axis of the wobble plate at said forward face is offset radially from the shaft axis at an angular position spaced approximately 90° from that of said rearmost portion of the forward face of the wobble plate; the amount of such offset being equal to the radial distance between said piston center circle and a chord of such circle, the length of said chord being equal to the stroke of said pistons between said rearward and forward positions; and means for reversing the angular position of said rearmost portion of the wobble plate, relative to the position of said offset, about the shaft axis.

17. A hydraulic machine as set forth in claim 16, in which said last named means comprises a key engaging a keyway of sufficient angular extent to permit a partial relative rotative movement between the position of said offset and the position of said rearmost portion of the wobble plate upon reversal of the direction of rotation of the shaft.
